(57) **CLAIM**

I claim the ornamental design for a corner guard, as shown and described.

DESCRIPTION

FIG. 1 is a top perspective view of the corner guard.

FIG. 2 is a first side elevation view thereof.

FIG. 3 is a second side elevation view thereof.

FIG. 4 is a front elevation view thereof.

FIG. 5 is a rear elevation view thereof.

FIG. 6 is a top plan view thereof.

FIG. 7 is a bottom plan view thereof; and,

FIG. 8 is a sectional view thereof taken along line 8-8 of FIG. 4.

The dot-dash-dot lines immediately adjacent to the shaded areas represent bounds of the claimed design. The broken lines illustrating portions of the corner guard, including the hatching for the internal structure shown in the sectional view of FIG. 8, are directed to unclaimed features and form no part of the claimed design.
